UNITED STATES PATENT OFFICE.

WILLY SCHNEIDER, OF BRIDGEPORT, CONNECTICUT, ASSIGNOR TO THE SALT'S TEXTILE MANUFACTURING COMPANY, OF BRIDGEPORT, CONNECTICUT, A CORPORATION OF CONNECTICUT.

MEANS FOR PRODUCING DESIGNS UPON PILE FABRICS.

1,183,243.

Specification of Letters Patent. Patented May 16, 1916.

Application filed May 8, 1914. Serial No. 837,255.

To all whom it may concern:

Be it known that I, WILLY SCHNEIDER, a subject of the Emperor of Germany, residing at Bridgeport, in the county of Fairfield and State of Connecticut, have invented certain new and useful Improvements in Means for Producing Designs upon Pile Fabrics, of which the following is a specification.

10 My invention relates to a novel means for producing ground effects upon pile fabrics, by which means I am enabled to turn out a fabric in any design required and also in close imitation of a natural skin with its 15 various shades of light and dark ground.

The invention will be understood by reference to the following description taken in connection with the accompanying drawings in which—

20 Figure 1 is a vertical section through a machine for winding the fabrics upon which the design or pattern is to be produced; Fig. 2 of a group of dies or design pieces to show the manner of placing them to produce the 25 desired effect; and Figs. 3 and 4 obverse and reverse sides, respectively, of the same die or design piece.

Coiled and twisted rubber in the shape of mat-like pieces have been used heretofore to 30 produce designs or ground effects. These, however, are expensive to make and they soon lose their original consistency and shape because of the heat to which they are subjected. Also being devoid of sharp edges 35 the design or pattern is not well defined, and, furthermore, because of the material used in their manufacture, and of the manner of making them, the patterns on the two sides of the mat are substantially similar. Other mats have been made of string 40 coiled and formed in like manner to the rubber, and paper has been tried, but the objections to both of these are many and obvious. They are easily deformed by the 45 action of the moisture and heat to which the fabric is subjected, and like the rubber mats have the same patterns on both sides. Moreover, the effect produced upon the fabric is unsubstantial and in many instances 50 barely perceptible.

One part of my invention relates to a novel form of design piece by which the design effects are produced. One form, as shown in Figs. 2, 3 and 4, consists of de-

sign pieces made of sheet metal, preferably 55 sheet brass, the blanks of which may be cut by hand, or they may be machine cut and of the same or varying outline. Design pieces are made from the blanks by passing them between engraved male and female 60 rolls, or by stamping them between male and female dies. The purpose of this part of the invention is to provide a design piece which shall be practically indestructible, 65 expansive and capable of extreme variability of design, and one which will produce in the fabric a sharp and well-defined design. I have shown in Figs. 3 and 4 the obverse and reverse sides, respectively, of such a design piece. In both figures the 70 countersunk or intaglio portions are stippled. Thus, in Fig. 3 the projecting or relief sections 1 of the design piece are the countersunk or intaglio portions on the reverse side of the design piece shown in Fig. 4. So also 75 the countersunk portions 2 of Fig. 3 appear as the relief portions of Fig. 4. The edges of the design pieces are relatively sharp and well defined and in practice have proved their utility and superiority over rubber and 80 other forms of so-called embossing mats heretofore used.

The manner of using the described design pieces to produce novel pattern effects will be understood by reference to Fig. 1, in 85 which the numeral 3 designates the frame of a machine in which is mounted a perforated metal mandrel 4 rotated by suitable means such as a worm wheel 5 driven by a worm 6 on the shaft of pulley 7. At one 90 end, and near the base of the frame, is mounted a roll 8 of canvas or like material, one end of which roll is carried up over the bar 9 and thence forward to the mandrel to which it is secured. This canvas strip is 95 stretched tight and is unrolled only when subjected to a considerable pulling force. It serves as a base or table on which is laid one of the two strips of pile fabric to be treated, said strip 10 being fed in between 100 the canvas strip and the mandrel with its finished face up.

As two strips of pile fabric may be treated at the same time, the second strip 11 is brought up from the opposite end of the 105 frame, as shown, and carried over the mandrel, and thence fed, with its finished face down, between the strip 10 and the mandrel

- so that the two finished faces of the fabrics are together at the point of winding. The canvas strip and the two pile fabrics being thus started, the operator places the metal design pieces upon the upper face of strip 10, as indicated at 12 in Fig. 1, placing them somewhat as shown in Fig. 2, so as to substantially cover the surface of the fabric, or so much thereof as is desired to be treated.
- 10 The rolling up on the mandrel 4 is continued until the mandrel is built up, the operator placing the design pieces on the strip 10 as the winding progresses. The layers on the mandrel are thus made up of the canvas strip and the two pile fabrics and between said goods the dies 12, all being wound into a tight compact roll. The goods upon which the designs are to be impressed are in a dry condition when wound upon the 20 mandrel and the pressure to which they are subjected causes the projecting or relief portions of the design pieces to sink into both pieces. Thus, if the design piece of Figs. 3 and 4 is placed on the strip 10 with its 25 obverse side upward, the reverse side, shown in Fig. 4, will be in contact with strip 10 and the obverse side in contact with strip 11. By placing the design pieces so that obverse and reverse sides are alternately up, in 30 rows transversely of the strip 10, a uniformity of effect will be produced in the two fabrics. This capability of reversing the design pieces and so producing similar effects in two pile fabric pieces at one operation, has not been accomplished heretofore, 35 so far as known to me. It also permits a much greater variability of design, and more natural effects than can be produced by any of the methods heretofore used. This 40 results from one side of the design piece leaving an impression which is clean cut and sharply defined, while the other side leaves somewhat of a blunt impression.
- When the winding is completed the mandrel is removed from the frame with the goods and the design pieces in place between the finished faces of the fabrics, and the roll is placed in a steamer for a sufficient length of time and pressure of steam to fix the 45 impressions made in the pile by the design pieces. The roll is then taken from the steamer, cooled and unwound when the canvas and design pieces are ready for further use.
- 50 Fabrics thus treated, can be made attractive in design and in close imitation of natural skins, and a further distinct advantage is that the design is firmly fixed or set and is held after long continued wear, and 55 is not distorted or affected by weather conditions. Another advantage from a manufacturing standpoint is that two pieces of goods may be operated upon at the same time, as each design piece makes an impression upon the lower as well as the upper
- piece of goods; an impression by the obverse side on one piece and by the reverse side on the other piece. The lobes or lateral extensions of the design pieces may be made so as to produce any desired outline, and, as 60 shown, the design is extended over both the body and lobes. It will be understood, of course, that the design contemplates not only the effect produced by the surface of the design pieces but by their outline or 65 configuration.
- If desired, the design pieces may be perforated in several places, as shown at 13 in Figs. 3 and 4, to permit the escape of steam therethrough. Also, instead of an 70 operator placing the design pieces in position on the lower piece of goods during the winding operation, they may be fastened, as shown in Fig. 2, to a blanket 14, as done heretofore with mats made of strings. This 75 saves the work of placing the design pieces by hand with each new roll.
- From the foregoing description it will be seen that my invention contemplates the use of a die or design piece made of material 80 which is practically indestructible and which will retain its original configuration under conditions of heat and moisture to which it is subjected after being rolled with the pile fabric. Also one which is non-compressible and flexible so that it may readily adapt itself to the curvature of the roll, and which will produce the same design, 85 without distortion, upon all convolutions of the roll. An additional advantage connected with my invention is, that a series 90 of design pieces may be made similar, both as to outline and as to surfaces, to thereby produce on the face of a pile fabric a uniform figure or design. Such design pieces 95 are not only non-compressible but of a permanent shape, having the advantages above 100 described.
- As I am the first, as I believe, to make a non-compressible design piece for producing 105 designs upon pile fabrics and to make a series of such design pieces similar as to outline and as to surface; and to produce 110 permanently shaped design pieces in duplicate thereby obtaining on the face of a pile 115 fabric a uniform figure or design, and to produce design pieces having complementary obverse and reverse impression surfaces, I desire to claim such features broadly 120 without reference to the particular material of which the design piece is made, and without limitation to any particular outline or configuration, or the particular design impressed upon the surface of the design pieces.
- 125 What I claim and desire to secure by Letters Patent of the United States is:
1. A design piece of material which is practically indestructible under heat and moisture when used as and for the purpose 130

described, having its edge cut to produce the desired configuration on a pile fabric.

2. A relatively thin and non-compressible design piece, adapted for producing designs upon pile fabrics, having its edge cut to produce the desired configuration.

3. A relatively thin and non-compressible design piece, adapted for producing designs upon pile fabrics, having its edge cut to produce the desired configuration, and its surface embossed.

4. A relatively thin and non-compressible design piece, adapted for producing designs upon pile fabrics, having its edge cut to produce the desired configuration, and its surface embossed with complemental obverse and reverse impression surfaces.

5. A design piece of relatively thin sheet metal having its edge cut to produce the desired configuration and adapted for use in producing a design upon pile fabrics.

6. A design piece of relatively thin sheet metal having its edge cut to produce the desired configuration and its surface embossed, and adapted for use in producing a design upon pile fabrics.

In testimony whereof I have hereunto signed my name in the presence of two subscribing witnesses.

WILLY SCHNEIDER.
